ABSTRACT

Apparatus for mounting distributor and dampening rollers in an offset printing machine. The distributor roller is journaled in a bearing secured in fixed bushing and the dampening roller is mounted on an arm extending from a body surrounding the bushing. The body is provided with key means permitting adjustable rotative positioning about the bushing.

OFFSET PRINTING MACHINES

BACKGROUND OF INVENTION

The present invention relates to offset printing machines and in particular to apparatus for resiliently mounting paired rollers such as the dampening and distributor rollers of such machines.

Paired rollers, such as the dampening and distributor rollers are generally required to be mounted in a manner which allows the pressure between them to be regulated. Conventionally means for urging rollers together include springs, eccentric bushings, set levers or other complex mechanisms. Such techniques are disadvantageous because they are not readily accessible for adjustment or modification during operation, and tend to prevent access to the other operating mechanism of the machine. A further drawback is that such devices are not capable of being precisely and sensitively adjusted to the exact pressure desired. Above all such devices, particularly the eccentric bushings are complex and expensive.

It is an object of the present invention to provide a simple and inexpensive mounting for paired rollers.

It is another object of the present invention to provide an improved assembly for rollers, such as the distributor and dampening rollers, in offset printing machines.

It is another object to provide an offset printing machine with apparatus for easily controlling the pressure between paired cooperative rollers.

It is a specific object of the present invention to provide an improved apparatus for adjustably mounting the dampening and distributor rollers of an offset printing machine.

Those objects and others as well as numerous advantages are obtained by the present invention, as will be seen from the following disclosure.

SUMMARY OF INVENTION

In accordance with the present invention apparatus for mounting paired rollers, such as the dampening rollers, of offset printing machines is provided having a support, a bushing fixed in the support and a roller rotatably journaled in the bushing and a holder is rotatably positioned over the bushing. The holder is provided with an arm supporting the other roller and key means located opposite to the arm to position the arm about the bushing. The key means extends within a slot transversely to the axis of the rollers so as to be slidable relative to the bushing. The key has an inclined face engaging the surface of the bushing positioning it whereby its interactions with the bushing causes the holder to rotate about the bushing into a fixed position.

In the preferred form the arm holding the second roller is eccentric to the diametric axis of the bushing, whereby gravity causes the arm to fall, moving the second roller into contact with the first roller. Spring means are also provided for resiliently urging the key into engagement with bushing. The key is provided with variable screw means accessible from without the frame to permit its simple adjustment.

Full details of the present invention are set forth in the following description and the accompanying drawings.

BRIEF DESCRIPTION OF DRAWINGS

In the description reference is made to the accompanying drawings in which:

FIG. 1 is a fragmentary elevational view, partially sectioned along line 1-1 of FIG. 2 of the dampening and distributor roller mounting assembly in accordance with the present invention; and

FIG. 2 is a sectional view taken along line 2-2 of FIG. 1.

The drawings show as much of a conventional offset printing press such as the type illustrated and described in "Photo-Offset Fundamentals" by John E. Gogoli (McKnight and McKnight Publishing Co., Bloomington, Ill., 1960, pages 158 et seq.) and commercially available as the "ATF Chief 20 Press," as is needed for a full understanding of this invention.

The actual printing mechanisms, implements, and the plural dampening mechanisms as well as the paper feeding and delivery devices have been omitted since they are not directly relevant to the present invention.

5 The present drawings further illustrate only one end of the assembly of distributor and dampening rollers. It is understood that each of the rollers are mounted at each of their ends to the spaced frames or supports of the machine. The mountings at both ends may, and are in fact preferably the same in order to maintain symmetry of design function and stress forces although they may however be different if desired. Therefore it is only necessary to show the mounting apparatus at one end of the device since by mirror image reproduction the opposite mounting can be easily visualized.

10 Still further, the concept of the present invention may be applied to the mounting of other paired engaging rollers and the fact that the drawings and description disclose the mounting of dampening and distributor rollers should not be taken as limiting in any way.

DESCRIPTION

Turning now to FIG. 1 there is seen a paired assembly of rollers comprising a distributor roller 10 and a dampening roller

25 10. The dampening roller 10 is of conventional construction having a necked down shaft end 13 rotatably journaled within a bearing 14, and axially secured by a C-clamp or retaining washer 16. The bearing 14, of conventional ball or roller bearing construction, is secured within a bore 18 of a bushing 20 which is itself fixedly mounted within the existing wall or frame support 22 of the offset printing machine. The bushing 20 is T-shaped, in longitudinal cross section, having a head 24 at its outer end and a cylindrical stem 26 extending inwardly and spacedly surrounding the shaft end 13.

30 35 Mounted to swing about the bushing 20 is a dampening roller holder, generally depicted by the numeral 28. The holder 28 comprises (FIG. 2) a body 30 in which is formed a bell shaped cavity 32 having straight side walls 34, spaced apart substantially equal to the diameter of the bushing stem

40 26, and an arch shape roof spaced above the bushing. The body has a boss 38 extending from its upper exterior and a boss 40, extending outwardly normal to the axle 13 of the distributor roller 10. Extending from the upper boss 38 of the

45 holder body 30 is an eccentrically directed arm 42 provided with a U-shaped cut out 44 receiving the axle 46 of the dampening roller 12. The arm 42 and the cut out 44 are directed at an angle to the distributor roller 10 so that gravity will normally cause it and the body to rotate toward the distributor

50 55 roller 10, to maintain the dampening roller 12 in contact with the distributor roller 10. The extent of the bias determines the pressure the dampening roller exerts on the distributor roller. The holder 28 is prevented from movement axially by a retaining

55 58 washer 50 and fastener 52, such as a C-clamp, urging the holder body 30 against the head 24 of the bushing 20.

The body 30 of the holder 28 is provided with a cylindrical slot or key way 54 extending through the boss 40 transversely to and beneath the cylindrical stem 26 of the bushing. Located

60 65 within the transverse key way 54 is a generally cylindrical feather key 56 having an inclined or sloping upper flat surface 58 adapted to face and engage the bushing stem 26 and a terminal upwardly sloping gib head 60. The sliding key 56 is adjustably secured with the key way bore 54 by a headed screw

62 having a threaded inner end 64 and engaging within a mating threaded hole 66 in the feather key. The screw 62 has a revolving cylindrical retaining ferrule 68 about which a compression spring 70 is located. The compression spring 70 is urged against the boss 40 and the head of the screw 62 to

70 75 maintain the screw in proper axial tension. The screw 62 is prevented from axial movement by a bar 72 which fits with a circular groove 74 cut within the exterior of the screw ferrule 68. The bar 72 is secured to the body boss 42 by a suitable screw fastener 76. Thus by rotating the screw 62 the slide key

75 can be reciprocated within the bore 54 so that its inclined sur-

face 58 variably engages the surface of the bushing. The oblique surface of the key is urged against the bushing 20. Because the bushing is fixed against rotation in the wall of frame support, the adjustment of the feather key causes the holder 28 to rotate about the bushing 26. The upper boss 40 of the body is provided with still another bore 78, diametrically opposed to the key 54, in which is mounted a sliding contact member 80 and compression spring 82 constantly urging the contact into engagement with the top of the bushing so as to exert a bias on the key 54.

As a result of this construction the interaction, of the feather key and the adjustment of its inclined surface, the resilient sliding contact at the upper boss, and the effect of gravity on the eccentric arm causes the holder 28 to be urged in an accurate direction biasing or pressing the dampening roller 12 against the surface of the distributor roller 10.

In operation, variable adjustment of the pressure between the rollers is obtained by turning the screw 62 to shift the position of the feather key 56. As the key changes its position the holder 28 is rotated, swinging the dampening roller 12, held by the arm 42 into more or less compression against the surface of the distributor roller. The compression spring and contact member are counter biasing means serving to maintain the holder secure and vibration free. The gib head 60 prevents untimely extraction of the key 54.

It will then be seen that a simple mechanism is provided by which the pressure between dampening and distributor rollers can be effectively varied. The present mechanism is free of any complicated cam, eccentric bushing or heavy spring biasing means and adjustment can be made freely and easily by rotation of a single screw, which is readily available without the dismantling or removing any part of the roller mechanism or machine. The degree of pressure may be readily set at any desired sensitivity levels and maintained threat during operation.

Various changes and modifications may be made particular without departing from the present inventive concept. In particular the shape of the holder, body and dampening roller carrying arms may be readily changed. The type of key and screw adjustment means may be modified as can other minor details. It is therefore intended that the present disclosures be illustrative only of the present invention and not limiting thereof.

What is claimed:

1. Apparatus for resiliently mounting a pair of engaging rollers in an offset printing machine comprising a support, a bushing fixedly secured within said support, one of said rollers being rotatably journaled within said bushing, a holder rotatably mounted about said bushing said holder

having an arm extending therefrom in which the other of said rollers is secured, a feather key located within said holder opposite said arm, and transverse to the axis of said bushing, said key having an inclined face adapted to engage the surface of said bushing and

means for adjusting the position of said key within said holder to cause said holder to be rotatably adjustable about said bushing in response to the relative position of the inclined surface of the key the surface of the bushing.

2. The apparatus according to claim 1 wherein the arm extends eccentrically from the holder, toward said one roller to urge said other roller in contact therewith by gravity.

3. The apparatus according to claim 1 including spring means for resiliently biasing said key against said bushing.

4. The apparatus according to claim 3 wherein said spring means includes a compression spring and a slidable contact member located in a bore opposite to said key to thereby exert a bias on said bushing diametrically opposed to said key.

5. The apparatus according to claim 4 wherein said key is provided with a gib head at one end to limit axial movement thereof relative to said bushing.

6. The apparatus according to claim 3 wherein the means for adjusting said key comprises a screw having an end extending axially within said key, a revolving retaining ferrule fixedly secured to said holder and a head extending outwardly of said holder whereby rotation of said head causes movement of said key relative to said holder.

7. The apparatus according to claim 5 wherein said screw is provided with a compression spring about said ferrule for maintaining said screw heat biased with respect to said holder.

8. The apparatus according to claim 1 wherein said holder includes a body having an internal cavity for receiving said bushing, said cavity having parallel side walls spaced a distance substantially equal to the diameter of said bushing, an arcuate top wall and an open bottom, spaced apart a distance substantially greater than the diameter of said bushing, a slot formed in said body transverse to said bushing adjacent said key being received in said slot, and resilient means extending from said arcuate top normal to said bushing to urge said body upwardly whereby said key engages said bushing.

9. The apparatus according to claim 8 wherein said bushing is T-shaped having its head located outwardly of said support and a cylindrical stem extending through said support to surround the axle of said roller, and means for axially securing said holder body on said bushing, said securing means urging said body against the inner face of said support and said bushing against the outer face of said support.

10. A distributor and dampening roller assembly for an offset printing machine according to claim 1, wherein said rollers have extending axles at each end.
